(57) CLAIM

The ornamental design for a furniture handle, as shown and described.

DESCRIPTION

FIG. 1 is a front perspective view of the furniture handle;
FIG. 2 is a bottom perspective view of the furniture handle;
FIG. 3 is a front view thereof;
FIG. 4 is a top view thereof;
FIG. 5 is a bottom view thereof;
FIG. 6 is a side view thereof;
FIG. 7 is an opposite side view thereof;
FIG. 8 is a rear view thereof;
FIG. 9 is a rear perspective view of the furniture handle; and,
FIG. 10 is a side perspective view of the furniture handle.
The broken lines shown in the drawings illustrate portions of the furniture handle that form no part of the claimed design.
